UNITED STATES PATENT OFFICE

WALTER MYERS, OF BRIDGEPORT, CONNECTICUT, ASSIGNEE TO THE SINGER MANUFACTURING COMPANY, OF ELIZABETH, NEW JERSEY, A CORPORATION OF NEW JERSEY

AUTOMATIC EMBROIDERING MACHINE

Application filed November 5, 1923. Serial No. 672,718.

This invention relates to improvements in universal-feed embroidering machines and more particularly in the type of embroidering machines well known in the art as the 5 "Bonnaz" machine, based upon the disclosure in the U. S. patent to A. Bonnaz, No. 83,910, Nov. 10, 1868.

The "Bonnaz" type of embroidering machine generally includes a universal-feed 10 mechanism of which the direction of work-advancing action is controlled by a hand-crank and also a manually controlled stop-motion device for determining the period of operation of the stitch-forming mechanism. 15 Modifications of this type of machine have heretofore been disclosed in which a pattern-cam was embodied in the machine for automatically determining the direction of feed, and automatic controlling devices for the 20 stop-motion have also been added in certain instances for determining the period of operation of both the stitch-forming and feed- 25 ing mechanisms to produce an embroidery design predetermined by the pattern-cam and the operative connections therewith. Automatic machines of this character as heretofore constructed are, however, extremely limited as to the character of the product.

The present invention has for its primary 30 object to provide a pattern-cam controlled universal-feed embroidering machine capable of automatically producing a large variety of designs from each pattern-cam without requiring the services of a skilled operator.

Another object of this invention is to provide an automatic control of the operation of the stitch-forming mechanism independently 40 of the period of operation of the feed-direction controlling mechanism whereby certain portions of the embroidery designed determined by the pattern-cam may be automatically omitted in the production of variations of the original design.

45 A further object of this invention is to provide a continuously effective automatic feed-direction control and an automatic intermittently effective control of the stop-motion device to both start and stop the operation 50 of the stitch-forming mechanism.

This invention has for a still further object to provide adjustable means for varying the automatic action and inaction of the stop-motion device in a machine of this character.

Other objects of the present invention will be apparent from the following description and claims.

In the preferred embodiment of the invention, the present improvements have been applied to the well known Singer universal feed embroidering machine of which the needle and feed-actuating mechanisms are constructed substantially in accordance with the disclosure in my prior U. S. Patent No. 1,325,033, of Dec. 16, 1919. In order to automatically control the direction of feed, a pattern-cam is journaled upon a transverse blind-axle supported in a suitable bracket upon the overhanging arm of the machine and this pattern-cam is intermittently actuated by means of a ratchet-and-pawl device operatively connected with the continuously rotated pulley-shaft, the operative connections including an eccentric adjustable into a plurality of positions of predetermined degrees of eccentricity to vary the size of the embroidery design produced. By actuating the pattern-cam from the pulley shaft instead of from the needle-bar reciprocating shaft, the pattern-cam is continuously rotated during the rotation of the pulley shaft regardless of the action and inaction of the stitch-forming mechanism. The pattern-cam vibrates a lever having a rack in mesh with a pinion clutched upon the usual feed-direction determining shaft, thereby automatically controlling the direction of feed.

In order to automatically control the action and inaction of the stitch-forming mechanism, the pattern-cam is provided on its periphery with a plurality of adjustable studs arranged to at predetermined intervals engage and shift a lateral arm of a rock-shaft to cause a tappet movable with said rock-shaft to automatically control the action of the usual stop-motion device provided in the "Bonnaz" embroidering machines. This stop-motion control serves to both start and stop the action of the stitch-forming and

feeding mechanisms during the continuance of the operation of the pattern-cam to control the direction of feed.

In the accompanying drawings, Fig. 1 is a front side elevation, partly in section, of an embroidering machine embodying the present improvements. Fig. 2 is a perspective view, partly in section, of the pattern-cam actuating and stop-motion controlling connections viewed from the rear, the bracket-arm of the machine being shown in dotted lines. Fig. 3 is a top plan view of the pattern-cam actuating adjustable eccentric. Fig. 4 is a perspective view of the elements of the adjustable eccentric of Fig. 3, shown in detached relationship. Fig. 5 is a detail perspective view of the detachable cover-plate of the arm-standard, in which is journaled the stop-motion controlling shaft. Fig. 6 is a sectional view of the pattern-cam and ratchet-wheel, together with their supporting means. Fig. 7 is a transverse section through the flange of the stop-motion controlling rock-shaft. Fig. 8 is a transverse section through the bearing boss of the front cover-plate. Fig. 9 is a detail view of the pattern-cam driving pulley-shaft gear. Fig. 10 is a detail view of the looper actuating eccentric. Figs. 11 to 15 inclusive are outline views of several embroidery designs produced from one pattern-cam. Figs. 16 and 17 are outline views produced from different pattern-cams. Figs. 18, 19 and 20 illustrate a few outline variations which may be produced from the pattern-cam designed to effect the outline of Fig. 16.

Referring to the drawings, the present improvements are shown as embodied in an embroidering machine having a cloth-plate base 1 from which rises the standard 2 of a tubular overhanging bracket-arm 3, terminating in a head 4. Journaled in suitable bearings provided in the standard 2 is the main or pulley shaft 5, carrying a belt-pulley 6 and counter-bored at its inner end to receive the reduced extremity 7 of a needle-actuating shaft 8. The shaft 8 is as usual provided at its forward end with an actuating crank (not shown) for vertically reciprocating the needle-bar driver 9 operatively connected with the needle-bar 10, reciprocating within but constrained to rotate with a cylinder 11 journaled for rotation in suitable bearings provided in the head 4. The needle-bar 10 carries at its lower end a hook-needle 12 which coacts below the work with a suitable looper (not shown) to draw loops of thread, directed to the looper from the supply-spool 13, through the work and enchain the same above the work. It is immaterial, however, for the purposes of the present invention, whether the thread is enchained above or below the work, or what is the particular type of stitch-forming mechanism employed.

A feeding foot 14 derives its feeding move-

ments from a rotary cam 15 upon the shaft 8 through the intermediary of a lever 16 and a sliding sleeve 17 transmitting reciprocatory movements to the usual cam-sleeve 18 upon the cylinder 11. The rising and falling movements of the feeding foot 14 are derived from a rotary cam 19 upon the shaft 8 and are transmitted to the feeding foot by a lever 20. A work-holding nipple 21 is vertically reciprocated alternately with the feeding foot 75 from the feeding foot lifting cam 19. No detailed description is herein presented of the needle-bar reciprocating connections or of the feed-actuating connections, inasmuch as the operative mechanism for these elements 80 and its mode of operation in a "Bonnaz" machine are extremely well known and as the particular type employed in the present machine is fully shown and described in my prior Patent No. 1,325,033 hereinbefore referred to.

As is usual in machines of this class, the feeding foot 14 is supported for universal feeding movements in the plane of the cloth-plate 1, the direction of feed being controlled by rotating the cylinder 11 which carries a rectangular guide-block 22 slidably engaged by a feed-collar 23 embraced by a feed-ring 24 upon the usual feeding foot carrying bar 25. In order to rotate the cylinder 11, there is secured thereupon a bevel-gear 26 in mesh with a similar gear 27 upon the forward end of a feed-direction determining shaft 28 suitably journaled in the overhanging arm of the machine. At its rearward end the shaft 28 is geared to the upper end of a vertical shaft 29 of which the opposite end is geared in like manner to a sleeve 30 journaled for rotation in but held against endwise movement by bearings provided below the cloth-plate 1. Splined to the sleeve 30 for reciprocatory movement therein and rotary movement therewith is a looper-actuating shaft 31, carrying at its forward end a looper-actuating spiral 32 and suitably connected at its opposite end with a lever 33 fulcrumed upon a lug 34 depending from the cloth-plate 1. The lever 33 is rocked by means of a pitman 35 having a strap embracing an eccentric 36 secured upon the shaft 8. If desired, the sleeve 30 may be operatively connected with a hand-crank 37 as in machines of prior construction, whereby when the automatic controlling mechanism hereinafter referred to is thrown out of action, the direction of feed 100 is manually controlled as heretofore.

It will be understood that as usual the reciprocations of the looper-shaft 31 from the eccentric 36 cause the operation of the usual looper (not shown) to coact with the needle 125 in the formation of stitches, while the rotation of the looper-shaft 31 maintains the timing of action of the looper necessary to coact with the needle as the latter rotates in accordance with the change in the direction of 130

feed under the controlling action of the shaft 28. This portion of the mechanism remains substantially as in machines of prior construction.

5 The needle and feed-actuating shaft 8 is not permanently secured to the pulley-shaft 5 but may be coupled thereto and uncoupled therefrom by means of a stop-motion device of well known construction. This device 10 comprises essentially a collar 38 loosely journaled upon the shaft 8, said collar being provided with a cam-groove 39 and a coupling-pin 40.

15 The coupling pin 40 is slidably disposed in an aperture 40^x provided in the eccentric 36 which is fast on the shaft 8 whereby the collar 38 is caused to rotate with the shaft 8. Under the action of a spring 41, the collar 36 is urged to cause the pin 40 to enter a suitable aperture 109^x in a driving bevel-gear 109 secured for rotation with the pulley-shaft 5 and when said pin 40 is seated in the aperture 109^x, it is evident that the shaft 8 is coupled to the shaft 5 for rotation there- 20 with. The pin 40 is however normally held out of engagement with the bevel-gear 109, but within the eccentric aperture 40^x by means of a shift-lever 42 carrying at its upper end a roller 43 engaging the cam-groove 39. The shift-lever 42 is fulcrumed by means 25 of a pivot-screw 44 upon a block 45 suitably secured upon the bracket-arm standard 2. At its lower end the shift-lever 42 is adapted to be engaged by the nose 46 of the usual shift-lever controlling slide 47, guided for vertical 30 movement in a slideway provided in the block 45 and normally urged upwardly by means of a spring 48 to engage the lever 42. It will be understood that engagement of the nose 46 with the lever 42 prevents vibration of the latter under the action of the cam-groove 39 and consequently this engagement in the coupled relationship of the shafts 5 and 8 causes the collar 38 to be forced laterally against the 35 pressure of the spring 41 until the pin 40 is disengaged from the bevel-gear 109, whereby rotation of the shaft 8 ceases at a point pre-determined by a spring-pressed plunger 49 seated in the block 45 and engaging a suitable 40 stop-notch provided in the collar 38. In the manually controlled machines it has long been common to depress the slide 47 to start rotation of the shaft 8 by means of a lever 50 fulcrumed below the cloth-plate 1 and controlled from the hand-crank 37 and this 45 mechanism may, if desired, be retained in the present machine. In fact, up to this point the machine may be constructed substantially as heretofore, with the exception that the 50 bevel-gear 109 is substituted for the usual driving collar.

60 Referring now more particularly to the specific subject-matter of the present invention, means have been provided for automatically controlling the direction of feed

in place of the hand-crank 37, the latter when embodied in the present machine being free to rotate under the compelling action of the automatic control. This automatic control is derived from a pattern-cam 51 provided 70 on its rear face with a cam-groove 52 entered by a cam-roller 53 carried by a lateral arm 54 of a vibratory segment-lever 55. The forward end of the lever 55 is forked to provide the spaced arms, as 56, embracing the 75 bracket-arm 3 and pivotally secured upon opposite sides thereof by means of pintles, as 57, suitably secured upon said arms 56. At its opposite end the lever 55 is provided 80 with a segmental rack 58 engaging a pinion 59, loosely journaled upon the feed-direction determining shaft 28 and provided with laterally projecting clutch-teeth 60. The clutch-teeth 60 are adapted to engage similar teeth formed on a collar 61 suitably secured 85 upon the shaft 28 for rotation therewith, the driving engagement between the collar 61 and the pinion 59 being normally maintained by means of a coil-spring 62 interposed between a collar 63 on the shaft 28 and 90 a shouldered sleeve 64 secured upon the pinion 59. When it is desired to rotate the cylinder 11 to change the direction of feed independently of the automatic control there- 95 for, the pinion 59 may be shifted out of driving engagement with the collar 61 and to this end a shoulder 65 of the sleeve 64 is adapted to be engaged by a crank-pin 66 upon the end of a spindle 67, suitably journaled in the bracket-arm 3 and carrying an 100 operating hand-lever 67^x.

The pattern-cam 51 is loosely journaled upon a blind-axle 68 disposed transversely of the shaft 8 and secured in an apertured boss 69 of a bracket 70 secured by screws 105 as 71 upon the rear side of the overhanging arm 3. A shoulder 72 upon the axle 68 abuts against one face of the boss 69 and is held thereagainst by means of a nut 73 threaded upon the projecting end of the axle. Also 110 loosely journaled upon the blind-axle is a ratchet-wheel 74 secured to the pattern-cam 51 by means of screws 75 and a positioning pin 76. The ratchet-wheel 74 is yieldingly forced against a shoulder 77 upon the axle 68 by 115 means of a three-prong friction-spring 78 bearing against the front face of the pattern-cam with an adjustable pressure determined by a nut 79 threaded upon the front reduced end of the axle 68.

120 Journaled upon the enlarged portion of the blind-axle 68 between the shoulders 72 and 77 is the hub 80 of a two-armed pawl-actuating lever upon one arm 81 of which is pivotally secured a pawl 82 yieldingly maintained in engagement with the teeth 83 of the ratchet-wheel 74 by means of a flat spring 84 suitably secured upon the arm 81 and overlying a lug 85 projecting from the pawl on the opposite side of its pivotal point. 130

The other arm 86 of the pawl-actuating lever 81, 86, has a ball-and-socket connection with one end of a pitman 87 of which the opposite end is provided with a strap 88 embracing an adjustable eccentric 89 having an elongated shaft-aperture 90. The eccentric 89 is provided with a flange 91 supporting the eccentric-strap 88 and upon its upper surface said eccentric is formed with a transverse guide-rib 92 slidingly fitted in a transverse grooved guideway 93 provided in the lower surface of an eccentric-securing disk or member 94. The disk 94 is provided with a hub 95 secured by means of a set-screw 96 upon the upper end of a short vertical shaft 97 journaled in a flanged bearing sleeve 98 of which the flange 99 is secured by screws as 100 upon the bracket-arm 3. In its secured position, the disk 94 rests upon the shaft-bearing 98 and together with the flange 91 confines the strap 88 to its eccentric embracing position.

The elongated aperture 90 affords means permitting the eccentric 89 to be adjusted relative to the shaft 97 and in the present instance to be adjusted into positions of predetermined degrees of eccentricity. To this end, the disk 94 is provided with elongated apertures 101 entered by securing screws as 102 threaded into apertures 103 in the eccentric. As the elongated apertures 101 are parallel with the similar aperture 90, it is apparent that by slightly loosening the screws 102 the eccentric 89 may be readily shifted 35 in a right-line in the guideway 93, as for instance by bearing upon the pitman 87. The positions into which the eccentric is shifted are predetermined primarily for the purpose of accommodating the throw of the pawl 82 40 to the size of teeth of the ratchet-wheel 74, the latter being interchangeable with different teeth-size ratchet-wheels whereby the size of the embroidery figure may be altered. To this end, the disk 94 is provided with a plurality of apertures 104 which are disposed eccentric to the axis of the shaft 97 while a number of apertures 106 in the eccentric 89 are disposed substantially concentric to the periphery of the eccentric. Each of the apertures 104 may be brought into alinement with 50 a corresponding aperture 106 by adjusting the eccentric 89 as described, but no two apertures 104 are simultaneously in alinement with two apertures 106. By dropping a positioning pin 107 into aligned apertures 104, 106 and tightening the screws 102 the eccentric 89 is positioned to effect a predetermined throw of the pawl 82, the apertures 104 and the ratchet-wheels 74 being preferably correspondingly labeled, whereby the correct throw may be instantly obtained for the ratchet-wheel selected.

In order to rotate the eccentric 89, the shaft 97 carries a bevel-gear 108 in mesh with 65 the driving gear 109. By driving the pat-

tern-cam from the pulley-shaft 5 which is capable of being rotated independently of the needle and feed-actuating shaft 8, the feed-direction control is effective whether or not stitches are being formed or the work advanced by the feeding-foot.

Automatic means are also provided to both start and stop the operation of the stitch-forming and feed-actuating mechanisms during the continuous automatic feed-direction control. To this end the pattern-cam 51 is peripherally provided with spaced series of spaced threaded apertures 110 and 111, the apertures of each series being in substantial circumferential alinement. Selectively threaded into certain of the apertures 110 are adjustable stop-elements in the form of headed screw-studs 112 and threaded in like manner into the apertures 111 are adjustable start-elements in the form of headed screw-studs 113. The paths of movement of both the stop and start screw-studs 112 and 113 intersect a cam-block 114 having, on a flat-face 115 thereof, the inclined block-deflecting cam-surfaces 116 and 117, both terminating in a central screw-clearance groove 118. The cam-block 114 is adjustably secured by means of a screw 119 and an elongated slot 120 upon a lateral arm 121 fixed upon a rock-shaft 122. The rock-shaft 122 is journaled in a bearing provided in a lug 123 and a boss 124 formed in a detachable cover-plate 125 secured by screws as 126 (only one of which is shown) entering threaded apertures 127 provided on the machine standard 3.

The rock-shaft 122 is preferably not directly journaled in its bearing, but is inserted in a rocking sleeve 128 and secured therein by means of a set-screw 129 threaded into a flange 130 of said sleeve. At its inner end there is secured upon the sleeve 128, by means of a set-screw 131, the hub of a tappet 132 positioned to engage the upper end of a stop-bar 133 fastened by screws as 134 upon the usual slide 47. Endwise movement of the sleeve 128 in its bearing is prevented by the flange 130 and the hub of the tappet 132 respectively engaging the boss 124 and the lug 123. The shaft 122 is endwise adjustable in the sleeve 128 to permit re-positioning of the arm 121 and the block 114 for different sizes of pattern-cams. To this end, said shaft 122 is provided longitudinally thereof with a V-shaped groove 135 entered by the pointed end of a positioning screw 136, whereby relative rotation between the shaft 122 and the sleeve 128 is prevented when the set-screw 129 is loosened to permit of the adjustment. By this means the angular relationship between the arm 121 and the tappet 132 is maintained regardless of the adjusted position of the block 114. In order to maintain the arm 121 in the stop and start positions determined by the elements 112 and 113, the rocking sleeve 128 is suitably frictioned. In the present in-

stance the necessary friction is obtained by inserting a friction-plug 137 of leather or other suitable material into a threaded aperture 138 provided in the lug 123 and forcing said plug to engage the sleeve 128 with an adjustable pressure determined by a set-screw 139 locked in position by a similar screw 140. To prevent overthrow of the tappet 132 under the combined action of the start-element 113 and spring 48 there is provided a stop-screw 141 threaded into the cover-plate 125 and adjustably secured thereupon by means of a lock-nut 142.

In the operation of the machine, the pulley-shaft 5 is continuously rotated, thereby continuously driving the eccentric 89 and pawl 82 whereupon the pattern-cam 51 is advanced step-by-step to continuously control the feed-direction through the vibrating lever 55 acting upon the pinion 59 in the normal clutched position of the latter upon the usual feed-direction determining shaft 28. The pattern-cam 51 is designed to so control the direction of feed as to produce a predetermined embroidery figure in the absence of any stop-motion control, i. e., during the continued operation of the stitch-forming and feed-actuating mechanisms. The pattern-cam 51 is of course readily interchangeable with others for effecting different predetermined designs and likewise the ratchet-wheel 74 may be readily removed and others substituted therefor whereby the feed-direction changes may have a greater or less speed-ratio with respect to definite work-advancing movements of the feeding foot. Should the stitch-forming and feed-actuating mechanisms be intermittently started and stopped while the feed-direction is under the continuous control of the pattern-cam, certain portions of the embroidery figure for which the pattern-cam is designed will be omitted and while the resulting embroidery figure will be of a continuous design, its contour or outline will vary considerably from that of the original design. Furthermore, other variations may be obtained by changing the stopping and starting times of the stitch-forming and feeding mechanisms with respect to the feed-direction control, whereby a very large variety of embroidery figures may be produced automatically from each pattern-cam.

In the present machine, as previously described herein, this intermittent operation of the stitch-forming and feed-actuating mechanisms is automatically controlled from the pattern-cam 51 by reason of the action of the screw-studs 112 and 113 upon the cam-block carrying arm 121. The pattern-cam 51 is advanced in the direction of the arrow shown in Fig. 1 causing a start screw-stud 113 to engage the inclined cam-surface 117 whereby the arm 121 is rocked rearwardly in the direction away from the operator. This causes the tappet 132 to engage the upper end of the

bar 133 and depress the nose 46 of the slide 47, whereupon the spring 41 is free to shift the collar 38 to couple the shafts 5 and 8, the shift-lever 42 being now free to vibrate. This brings the needle and feed-actuating mechanisms into operation. The stop screw-studs 112 alternate with the start-studs 113 and consequently after a predetermined number of stitches have been completed, a stop-stud 112 engages the inclined cam-surface 116 to swing the arm 121 towards the operator. This raises the tappet 132 to permit the spring 48 to shift the nose 46 into the path of movement of the shift-lever 42, restraining the latter from vibration whereby the collar 38 is shifted to disengage the coupling-pin 40 from the bevel-gear 109. Consequently, the stitch-forming and feed-actuating mechanisms, which are directly brought into operation by the shaft 8 will be intermittently started and stopped, with the feed-direction shaft 28 under the continuous control of the pattern-cam. Therefore, while a continuous seam is being formed, it is formed intermittently and certain portions of the original design will be omitted, the omitted portions being selective by the repositioning of the stop and start studs 112, 113 upon the periphery of the pattern-cam. By means of a suitable index system the desired design may evidently be readily predetermined.

It may be necessary or desirable to at times change the direction of production of the embroidery design as for instance when approaching the edge of the garment or when a definite form is being produced, in which case the pinion 59 is unclutched from the shaft 28 by manipulation of the hand-lever 67*, whereupon the cylinder 11 is free to be rotated to obtain the desired direction. Fig. 15 for instance illustrates a change at right-angles of the direction of production of the design.

A few embroidery designs are outlined in Figs. 11 to 14 inclusive, which may be produced by means of a pattern-cam having a cam-groove of the configuration illustrated for instance in Fig. 1. It will be observed that the corners *a* are rounded in Fig. 11, this being the design produced in the absence of any stop-motion control, i. e., the design predetermined by the pattern cam per se. It will be apparent that it would be extremely difficult, if not impracticable, to provide a pattern-cam cam-groove sufficiently sharp to directly produce a right-angled corner in an embroidery design by merely controlling the direction of feed. The same effect is produced however by the present machine by stopping the stitch-forming and work-advancing mechanisms to omit the round corner stitches of Fig. 11 and automatically restarting the stitch-forming and work-advancing mechanisms at a predetermined period in which the direction of feed is at right

angles to the previous direction, whereby an embroidery design having the outline of Fig. 12 is produced.

In case it is desired to maintain the outline 5 of the design shown in Fig. 12 with a less number of stitches of the same length to effect the similar but smaller outline of Fig. 13, it is merely necessary to change the speed ratio between the feed-direction control and the work-advancing movements of the feeding foot. In the present instance this is accomplished by an adjustment of the eccentric 89 and preferably also by the substitution 10 of a different toothed ratchet-wheel for that previously employed. To produce the outline shown in Fig. 14, the same throw of the eccentric 89 may be employed as is used for producing the design of Fig. 12 but the stop-studs 112 are repositioned in the apertures 110 to omit a portion of the design, as 15 will be apparent.

In Figs. 16, 18, 19 and 20 are illustrated a few designs capable of being produced by a pattern-cam of which the cam-groove has 20 a different configuration from that shown in Fig. 1 and which is designed to produce the embroidery outline of Fig. 16 in the absence of any stop-motion control. To produce the outlines of Figs. 18, 19 and 20 the start- and 25 stop-studs 112 and 113 are both repositioned, but if the design of any one of these figures is to be maintained in larger or smaller outline, i. e., with a different number of stitches 30 of the same length, the throw of the eccentric 89 is correspondingly altered. Fig. 17 illustrates a still further design which may 35 be automatically reproduced without the employment of any stop-motion control from a pattern-cam having the necessary cam-groove configuration. By the proper repositioning 40 of the stop-motion controlling elements, the portion for instance between the lines *b*, *b* and *c*, *c* may be omitted to produce substantially the design of Fig. 16.

45 It is to be understood that the embroidery designs illustrated are only a few of those capable of being made from each pattern-cam and that the variety of designs which may be produced is almost endless, each of 50 which may however be predetermined by a suitable index system setting forth the positions of the start- and stop-studs 112 and 113 and the throw of the eccentric 89. The dis- 55 connectible feature of the pinion 59 under the action of the lever 67* is of some importance as it permits changing the direction of production of the embroidery design without requiring the turning of the work itself. 60 The advantage of this feature will be apparent when it is considered that without it, large pieces of work such as table-cloths would have to be turned about the stitching point to obtain the desired new direction. 65 Fig. 15 as previously stated illustrates the

turning of a square corner while producing the design of Fig. 13.

Having thus set forth the nature of the invention, what I claim herein is:—

1. In a sewing machine, the combination 70 with stitch-forming and feed-actuating mechanisms, of mechanism operating during the formation of a seam of continuous stitches to automatically stop and automatically restart the operation of said stitch-forming and feed-actuating mechanisms subsequently to 75 the formation of the initial stitch of said seam of continuous stitches.

2. In a sewing machine, the combination 80 with stitch-forming and feed-actuating mechanisms, of intermittently effective mechanism for automatically starting and stopping the operation of said stitch-forming and feed-actuating mechanisms at predetermined intervals in the formation of a seam of continuous 85 stitches.

3. In a sewing machine, the combination 90 with stitch-forming and feed-actuating mechanisms, of intermittently effective controlling mechanism for automatically starting and stopping the operation of said stitch-forming and feed-actuating mechanisms at predetermined intervals in the formation of a seam of continuous stitches, and means permitting selective predetermined 95 times of effective action of said controlling mechanism.

4. In a universal-feed sewing machine, the combination 100 with stitch-forming and feed-actuating mechanisms, of continuously effective automatic feed-direction controlling means, and mechanism for automatically starting and stopping the operation of said stitch-forming and feed-actuating mechanisms during the effective action of said controlling means. 105

5. In a universal-feed sewing machine, the combination 110 with stitch-forming and feed-actuating mechanisms, of mechanism for automatically stopping the operation of said stitch-forming mechanism, and feed-direction controlling means automatically operative independently of the operation of said stitch-forming mechanism.

6. In a universal-feed sewing machine, the combination 115 with stitch-forming and feed-actuating mechanisms, of mechanism for automatically stopping the operation of said feed-actuating mechanism, and feed-direction controlling means automatically operative independently of the operation of said feed-actuating mechanism. 120

7. In a universal-feed embroidering machine, the combination 125 with stitch-forming and feed-actuating mechanisms, of a pattern-cam for automatically determining the direction of feed, intermittently effective controlling-mechanism for automatically starting and stopping the operation of said stitch-forming and feed-actuating mechanisms, and 130

means permitting selective predetermination of the times of effective action of said controlling mechanism.

8. In a sewing machine, the combination with stitch-forming mechanism including a reciprocating needle, and feeding mechanism for advancing the work past said needle, of automatically operative feed-direction controlling means for causing said stitch-forming and feed-actuating mechanisms to produce repetitions of a predetermined embroidery design in a seam of continuous stitches, and automatically acting mechanism for at intervals discontinuing the operation of both the stitch-forming and feeding mechanisms during the effective operation of said feed-direction controlling means whereby to omit a predetermined portion of said design in a seam of continuous stitches.
9. In a universal-feed embroidering machine, the combination with stitch-forming and feed-actuating mechanisms, of means for automatically controlling the direction of feed to effect a predetermined embroidery design in repetition in a continuous seam, and a disconnecting device permitting changing the direction of production of said seam at will.

10. In an embroidering machine, the combination with stitch-forming and feeding mechanisms for producing a predetermined embroidery design, of means for automatically controlling the effective action of said mechanisms to omit a predetermined portion of said design in a continuous seam, and means for at will changing the direction of production of said seam.

11. In a universal-feed embroidering machine, the combination with stitch-forming and feed-actuating mechanisms, of controlling means operatively connected with said feed-actuating mechanism for automatically determining the direction of feed, and a throw-out device for said controlling means permitting manual control of the direction of feed.

12. In a universal-feed embroidering machine, in combination stitch-forming mechanism, feed-actuating mechanism for advancing the work a predetermined stitch-length, automatic feed-direction controlling mechanism operatively connected with said feed-actuating mechanism for effecting a predetermined embroidery design, and adjustable means for effecting a predetermined change in size of the embroidery design while maintaining the same stitch-length.

13. In a universal-feed embroidering machine, in combination, stitch-forming mechanism, feed-actuating mechanism for advancing the work, a pattern-cam for automatically controlling the direction of feed to effect a predetermined embroidery design, pattern-cam actuating mechanism, and means for varying the effective action of said pat-

tern-cam actuating mechanism to effect a predetermined change in size of the embroidery design.

14. In a universal-feed embroidering machine, in combination, stitch-forming mechanism, feed-actuating mechanism for advancing the work, a pattern-cam for automatically controlling the direction of feed to effect a predetermined embroidery design, pattern-cam actuating means including a rotary eccentric, and means for varying the eccentricity of said eccentric a predetermined extent to effect a change in size of the embroidery design.

15. In an automatic embroidering machine, in combination, stitch-forming mechanism, feeding mechanism, automatic controlling means comprising a pattern-cam, and pattern-cam actuating means including a rotary eccentric, a rotary shaft, a member carried by said shaft upon which said eccentric is secured, and means permitting a relative predetermined degree of adjustment between said eccentric and member to obtain a definite degree of eccentricity of said eccentric with respect to the said shaft whereby the speed of movement of said pattern-cam may be predetermined.

16. In an automatic embroidering machine, in combination, stitch-forming mechanism, feeding mechanism, automatic controlling means comprising a pattern-cam, and pattern-cam actuating means including a rotary eccentric, a rotary shaft, a member carried by said shaft upon which said eccentric is secured, means permitting relative adjustment in a right line between said member and eccentric, and means for determining a plurality of adjusted positions of said eccentric with respect to said member whereby to predetermine the speed of movement of said pattern-cam.

17. In a universal-feed embroidering machine, the combination with stitch-forming mechanism, feed-actuating mechanism for advancing the work past said stitch-forming mechanism, and a feed-direction determining shaft, of automatic controlling means for said feed-direction determining shaft comprising a pattern-cam, pattern-cam actuating means, a vibratory lever actuated by said pattern-cam, a rack carried by said lever, a pinion loosely journaled upon the feed-direction determining shaft, and a clutch-device whereby said pinion and shaft may be at will connected and disconnected.

18. In a universal-feed embroidering machine, the combination with stitch-forming mechanism, and feed-actuating mechanism for advancing the work past said stitch-forming mechanism, of automatic feed-direction controlling means comprising a pattern-cam, actuating means for rotating said pattern-cam, and means for determining both the action and inaction of said stitch-forming

and feed-actuating mechanisms from said pattern-cam.

19. In a sewing machine, the combination with stitch-forming and feeding mechanisms, of a controlling cam, means for actuating said cam, a plurality of start and stop elements selectively disposed upon the periphery of said cam, and operative connections controlled by said start and stop elements for both starting and stopping the stitch-forming and feed-actuating mechanisms in the formation of a continuous seam.

20. In a sewing machine, the combination with stitch-forming and feed-actuating mechanisms, of a controlling cam, means for actuating said cam, a plurality of spaced start and stop elements selectively disposed in spaced paths upon said cam, and operative connections for intermittently starting and stopping said mechanisms under the controlling action of said elements.

21. In a universal-feed embroidering machine, the combination with stitch-forming and feed-actuating mechanisms, of a pattern-cam, means for actuating said cam, operative connections for controlling the direction of feed from said cam, a plurality of start and stop elements adjustably disposed upon said cam, and operative connections for both starting and stopping the operation of said stitch-forming and feed-actuating mechanisms under the controlling action of said elements.

22. In a sewing machine, the combination with stitch-forming and feed-actuating mechanisms, of a controlling-cam, means for actuating said cam, a plurality of start and stop-elements disposed upon said cam, a rock-arm provided with a plurality of cam-surfaces disposed in the path of movement of said elements, a stop-motion device, and operative connections between the rock-arm and said stop-motion device to intermittently start and stop the operation of said mechanisms under the action of said elements.

23. In a sewing machine, the combination with stitch-forming and feed-actuating mechanisms, of a controlling cam, means for actuating said cam, a plurality of start and stop-elements disposed upon said cam, a rock-arm provided with a plurality of cam-surfaces disposed in the path of movement of said elements, a stop-motion device, operative connections between the rock-arm and said stop-motion device to intermittently start and stop the operation of said mechanisms under the action of said elements, and means for determining the direction of feed from said controlling-cam.

24. In a sewing machine, the combination with stitch-forming and feed-actuating mechanisms, of a controlling cam, means for actuating said cam, a plurality of spaced start and stop elements adjustably disposed in spaced paths upon said cam, operative con-

nnections for intermittently starting and stopping said mechanisms under the controlling action of said elements, and means for determining the direction of feed from said controlling-cam.

In testimony whereof, I have signed my name to this specification. 70

WALTER MYERS.
